W. A. Rosenbaum
ATTORNEY

UNITED STATES PATENT OFFICE.

LEO WEISENBURGER, OF MOUNT VERNON, NEW YORK.

KNAPSACK.

SPECIFICATION forming part of Letters Patent No. 645,151, dated March 13, 1900.

Application filed August 31, 1899. Serial No. 729,026. (No model.)

To all whom it may concern:

Be it known that I, LEO WEISENBURGER, a subject of the Emperor of Germany, residing at Mount Vernon, in the county of Westchester and State of New York, have invented 5 certain new and useful Improvements in Knapsacks, of which the following is a full, clear, and exact description.

This invention relates to army-knapsacks, 10 the object being to produce an article of this character which may be used in case of an emergency as a shield against bullets of an enemy and which may be grouped or placed with others of its kind to form a temporary 15 redout or fortification, behind which a company of soldiers may intrench themselves to make a stand against an enemy.

To this end my invention consists of a knapsack provided with one or more bullet-proof 20 armored sides and with means whereby the knapsack may be made to stand upright upon the ground and other means whereby one or more knapsacks may be placed on top of each other to form a wall.

25 The invention will be described in detail with reference to the accompanying drawings, in which—

Figure 1 is a perspective view of a knapsack constructed in accordance with my invention, and Fig. 2 is a plan of the bottom of 30 the same with parts broken away.

Referring to the drawings by letter, A represents the knapsack proper. It is provided with the usual flap or lid a, which in this instance is made of two thicknesses of material a' a², secured together at the edges and forming a pocket in which is placed a sheet of metal b, extending substantially throughout the full dimensions of the flap. This metal 35 may be of aluminium or an alloy containing aluminium or of any other suitable bullet-proof material. Likewise this armor may be placed in the opposite wall of the knapsack—that is, the wall that rests against the back 40 of the wearer—but I prefer to put it in the flap, as described. A knapsack when made in this way may be a little wider and higher than usual in order to furnish as large a shield as possible.

45 At each of the lower corners of the knapsack I place spurs c. These are suitably hinged at said corners and are provided with springs c', which tend to fold them up against

the bottom of the knapsack in the position shown in Fig. 2, which is the normal position 55 when the knapsack is used only as a luggage-carrier.

When desired as a protection against bullets, the knapsack can be quickly removed from the shoulders and the spurs thrown out 60 to the position shown in Fig. 1 and forced into the ground, where they will support the knapsack in an upright position, and thus furnish a protection behind which a soldier may lie and fire at the enemy with little danger of 65 being hit himself. The knapsack in this position also affords a convenient rest for the gun of the soldier in firing.

To make a higher and more considerable fortification, the knapsacks may be stacked 70 on top of each other and side by side, and for this purpose I provide in the upper corners of the knapsack the pockets e e, which are merely sockets shaped to receive the spurs of another knapsack. When one of the knapsacks has been anchored in the ground, another may be placed on top of it and supported by the spurs passing into these sockets. Two or more may be placed on top of 75 each other in this way, forming a tier alongside of which other tiers may be arranged to form a continuous and substantial barricade. Extra knapsacks belonging to the wounded 80 or dead on the field can usually be obtained for this purpose.

Having described my invention, I claim—

1. A knapsack provided with spurs along one edge adapted to be forced into the ground to support it in an upright position and sockets along the opposite edge adapted to receive the spurs of another knapsack, for the purpose set forth.

2. A knapsack provided with bullet-proof armor and spurs along one edge adapted to be forced into the ground to support it in an 95 upright position, and sockets along the opposite edge adapted to receive the spurs of another knapsack whereby the knapsack may be used as a temporary fortification.

In witness whereof I subscribe my signature in presence of two witnesses.

LEO WEISENBURGER.
